UNITED STATES PATENT OFFICE.

JOHN M. MADIGAN AND DANIEL C. SMITH, OF LAWRENCE, MASSACHUSETTS.

MACHINE FOR SAWING SLOTS IN LASTS.

1,177,716.

Specification of Letters Patent.

Patented Apr. 4, 1916.

Application filed April 16, 1915. Serial No. 22,205.

To all whom it may concern:

Be it known that we, JOHN M. MADIGAN and DANIEL C. SMITH, citizens of the United States of America, and residents of 5 Lawrence, in the county of Essex and State of Massachusetts, have invented certain new and useful Improvements in Machines for Sawing Slots in Lasts, of which the following is a specification.

10 This invention relates to machines for sawing slots in the fore parts and heel parts of lasts, and has for its object the production of a device of this character in which the parts of the last may be accurately positioned during the slot cutting operation, and in which the work may be moved upwardly in relation to the slot cutting member during the operation of the latter.

15 The invention consists of certain novel features of construction and arrangement of parts which will be fully understood by reference to the description of the drawings and to the claims hereinafter given.

20 Of the drawings: Figure 1 represents a vertical section through a supporting bench and showing in elevation a slot cutting device embodying the principles of the present invention. Fig. 2 represents a horizontal section of the same, the cutting plane being 25 on line 2—2 on Fig. 1. Fig. 3 represents a front elevation of the lower end of the vertical slide, its support, and the members coacting. Fig. 4 represents a side elevation of the lower end of said slide and the work 30 supporting plate hinged thereto, and Fig. 5 represents a front elevation of the upper 35 end of the work supporting plate.

Similar characters designate like parts throughout the several figures of the drawings.

40 In the drawings, 10 is a bench or other support to which is secured a frame 12 having a downwardly extending plate 13. The upper end of the frame 10 is provided with 45 suitable bearings 14 in which is mounted a revoluble shaft 15 carrying a circular saw 16. The shaft 15 is adapted to be revolved by means of the pulley 17 in the direction of the arrow *a* on Fig. 1 of the drawings. 50 To the front face of the downwardly extending plate 13 are secured guide plates 18 between which a slide 19 is adapted to vertically reciprocate. In the block 20 se-

cured to the lower end of the member 13 is a threaded member 21 adapted to limit 55 the downward movement of the slide 19 while another member 22 is mounted to reciprocate in said block 20 and is threaded to an ear 23 extending forwardly from said slide 19. The member 22 is provided with 60 a shoulder 24 which is adapted to coact with the lower face of the block 20 to limit the upward movement of said slide 19.

The slide 19 is provided with two ears 25 to which is hinged, by means of the pin 65 26, a work supporting plate 27. Near its upper end the plate 27 is provided with a slot 28 extending therethrough on each side of which is a positioning rib 29. The plate 27 has secured to its front face at its upper 70 end two parallel strips 30 having ears 31 thereon to which is pivoted a U-shaped member 32 having centrally disposed therein a tubular hub 33 in which is mounted a reciprocating member 34 having a pin 35 75 therein extending through a slot 36 in the hub 33 to prevent said member 34 from rotating therein. The U-shaped member 32 also carries an adjusting member 37 the inner end of which is threaded to the member 34. This member 37 is provided with a collar 38 interposed between the U-shaped member 34 and a bar 39 secured thereto, thereby preventing any end movement of the member 37. 85

80 The machine shown in the drawings and herein described is intended especially for cutting slots in the fore part and heel part of a particular kind of transversely divided lasts in the construction of which a cylindrical hole is bored upwardly from the bottom of the last and is then transversely divided on the axis of said cylindrical hole. When the last is transversely divided the adjacent spaces of the heel and toe parts 90 thereof will each have a semi-cylindrical groove therein extending part way toward the top of the last. This semi-cylindrical hole serves to register the toe part or heel part of the last on the work support, the shoulder at the upper end of the semi-cylindrical groove resting upon the forwardly extending ribs 29 formed upon the work supporting plate 27. These ribs 29 are curved to fit the semi-cylindrical groove in 100 the toe and heel parts of the last, as shown 105

in section in Fig. 2 of the drawings. When either the toe part or heel part of the last is thus positioned upon the ribs 29 the U-shaped member 32 is brought into the position shown in Fig. 1 of the drawings, and then the member 37 is rotated to force the forked end of the clamping member 34 against the comb of the toe part or the rear end of the heel part, thereby clamping the part to be slotted securely against the work supporting plate 27. The work supporting plate 27 is adapted to travel toward and from the frame 12 between two guide members 40 which prevent lateral movement of said plate.

Mounted in the guide members 40 and extending from one to the other is a rod 41 which serves to limit the outward movement of the plate 27. Normally the work supporting plate 27 is held against the rod 41 by means of a rod 42 mounted in bearings in the downwardly extending member 13 and a member 43 secured to the under face of the bench or other support 10. This rod 42 is provided with a projecting flange 44 between which and the bearing 43 is a spring 45, the tension of which retains the work supporting plate 27 normally in its outer position. A member 46 also mounted in the bearing block 43 and threaded to the downwardly extending plate 13 is adapted to be rotated by the handle 47 to adjust its forward end thereby regulating the rearward movement of the plate 27. The slide 19 has connected to its upper end a flexible member 48 passing over a pulley 49 revolvably mounted in ears 50 extending from the rear face of the plate 13, the opposite end of said flexible member 48 being secured to a treadle 51 pivoted at 52. By depressing the treadle 51, the slide 19 may be raised carrying therewith the work supporting plate 27 and the parts supported thereby. The weight of the slide 19 will return it to its normal position when pressure is removed from the treadle. When the slot is being cut into the toe part or heel part of a last, the work supporting plate with the part of the last thereon is moved toward the frame 12, the saw 16 entering the slot 28 in the work supporting plate 27 and cuts the required slot in the work support on said plate.

If it is desired to cut the slot downwardly through the bottom of the last, this may be accomplished by depressing the treadle 51 while the saw is rotated, thus moving the work upwardly relatively to the rotating saw. During the rotation of the saw and when it is not being used upon the work the work supporting plate 27 is always in front of the saw and prevents the hands of the workman from coming into contact therewith, the spring 45 being stiff enough to prevent accidental rearward movement of

the work supporting plate 27. When the work is mounted upon the plate the operator forces the plate with the work thereon into contact with the saw, and while the operation is being performed, the teeth of the rotating saw are embedded in the work itself, and any accidental cutting of the operator's hands is effectually prevented. This makes a very simple and effective device for cutting the slots in the toe and heel parts of lasts, and while the slot in each part is cut independently of the other, owing to the two parts of the last being registered upon the same work supporting ribs, the slots cut are always in alinement when the toe and heel parts are assembled in the finished last.

It is believed that the many advantages of this invention will be fully apparent from the foregoing description.

Having thus described our invention, we claim:

1. A machine for forming a groove or mortise in a work blank having a recess in one face, comprising a rotary cutter, a plate pivoted to swing toward and from the cutter on an axis in or parallel to the plane of the plate and having a slot to receive the cutter and ribs on the edges of said slot adapted to fit the above mentioned recess in the work blank.

2. A machine for forming a groove or mortise in a work blank having a recess in one face, comprising a rotary cutter, a plate pivoted to swing toward and from the cutter on an axis in or parallel to the plane of the plate and having a slot to receive the cutter and ribs on the edges of said slot adapted to fit the above mentioned recess in the work blank; and clamping means pressing the work toward the plate and upon said ribs.

3. A machine for forming a groove or mortise in a work blank having a recess in one face, comprising a rotary cutter, a plate pivoted to swing toward and from the cutter on an axis in or parallel to the plane of the plate and having a slot to receive the cutter and ribs on the edges of said slot adapted to fit the above-mentioned recess in the work blank; and clamping means pressing the work toward the plate and upon said ribs, said clamping means consisting in part of a nonrevoluble slidable member having a forked end adapted to engage the work blank.

4. In a machine of the class described, the combination of a circular saw; means for driving said saw; a slotted hinged plate having work supporting ribs on opposite sides of said slot and adapted to be moved toward said saw; and a slide adapted to reciprocate vertically to which said work supporting plate is pivoted.

5. In a machine of the class described, the combination of a circular saw; means for driving said saw; a slotted hinged plate hav-

ing work supporting ribs on opposite sides of said slot and adapted to be moved toward said saw; a slide adapted to be reciprocated vertically by the operator during the sawing operation and to which said work supporting plate is pivoted; and means for predetermineding the movement of said slide in either direction.

Signed by us at 4 Post Office Sq., Boston, Mass., this 14th day of April, 1915.

JOHN M. MADIGAN.
DANIEL C. SMITH.
